UNITED STATES PATENT OFFICE.

JOHN S. MILLER, OF TRURO, CANADA.

CAR-STAKE.

SPECIFICATION forming part of Letters Patent No. 593,229, dated November 9, 1897.

Application filed June 5, 1895. Renewed May 18, 1897. Serial No. 637,122. (No model.)

To all whom it may concern:

Be it known that I, JOHN S. MILLER, a British subject, residing at Truro, in the county of Colchester, in the Province of Nova Scotia and Dominion of Canada, have invented new and useful Improvements in Car-Stakes, of which the following is a specification.

My invention relates to the stakes which are a necessity to the complete equipment of flat railroad-cars to use in securing loads of deals, lumber, round or square timber, in boxing for coal, &c., or in securing any material that is necessary to be secured on flat-cars or other conveyances by means of stakes; and the objects of my invention are, first, to provide a combination that can remain attached to the car or other conveyance when not in use, thus obviating the expense to the shipper of deals, &c., by rail of providing a new set of stakes and binding-gear each time the car is reloaded, and, secondly, to provide a stake that can be easily freed from the load when necessary and when not in use can be placed in a position that will leave the car in condition to be loaded or unloaded with gravel or other material not requiring the use of stakes. I attain these objects by the mechanism illustrated in the accompanying drawings, in which—

Figure 1 is an end elevation of the frame of a flat-car, showing two stakes in an upright position with the binder connecting them at the top. Fig. 2 is an edge view of the stake-socket. Fig. 3 is a front view of the same. Fig. 4 is a plan of the same. Fig. 5 is a side elevation of a part of the frame of a car, showing the stake turned down to a horizontal position and lying on the stake-rest. Fig. 6 is a side elevation of the stake. Fig. 7 is an edge elevation of the same.

In the drawings, A is an end piece of the car-frame. B is a side piece of the same frame.

P is the stake, which is of wood, about three inches square where it enters the shoe and about two inches by two and one-half inches at the top end and bound on the inner and outer edges by a continuous strip of thin iron to increase its strength and as a protection.

C is the stake-shoe, which is a case of thin

metal surrounding and protecting the lower end of the stake.

D D is the binding-rod, which is formed of light round iron and is secured to the stakes 55 by the rings K K.

E is the lock-lever, which is made of iron and which connects the two sections of the binding-rod and by which the proper binding tension is secured. 60

F is the keeper, which is of iron and which serves to keep the rod from being separated from the stakes when not in use.

G is the stake-rest, which is secured to the side frame of the car and in which the stake 65 rests when in a horizontal position.

H is a slot through the stake-shoe and stake through which the bolt I passes, connecting the stake to the socket. The bolt I after passing through the stake and socket continues through the side piece of the frame of the car and is secured on the inside of the frame by a nut and washer. 70

L is the stake-socket, which is of cast-iron and is secured to the side frame of the car by 75 the staple f in any required position for the purpose of holding the stake P. The lips n n project upward from the mouth of the socket for the purpose of allowing the stake to swing to a horizontal position on the pin I. This 80 socket can be used for stationary stakes without any change, if so desired.

J is a curved hook formed on the end of the lock-lever E and passes under the binding-rod D, holding the lever in place when in 85 use.

c c c are recesses near the top of the stake, in one of which the rings K K are placed when the tension is put on the binding-rod.

e is a groove on three sides of the stake- 90 socket, in which the staple f rests.

g is the hole in the lips of the stake-socket, through which the pin I passes.

In using the stake two of them are placed in upright positions in their sockets on opposite sides of the car before commencing to load or at any convenient time, and when the load is completed the binding-rod D D is placed in position across the top of it, the long arm of the lock-lever is held in an upright position, and the curved point of the short arm is engaged with a link of the chain 95 100

on the opposite section of the rod that will give the required tension for binding properly. The long arm of the lever is then brought down to a horizontal position, and the curved point J is inserted under the rod, thus maintaining the desired strain on the stakes.

When the load is to be removed, the lock-lever is released. The parts of the binding-rod are each swung to the outside of their respective stakes. Each stake can be then lowered to a horizontal position, as shown in Fig. 5, by first raising it in a perpendicular direction until the bottom of the slot H rests against the under side of the pin I, when it can then be swung down either to the front or rear until it rests in the stake-rest G, the taper on the outside of the stake-shoe allowing the stake to be readily freed from the load and in its

descent to clear the irregularities in the surface of side sills or other projections that may be on the side of the load.

What I claim as my invention, and desire to secure by Letters Patent, is—

In a car-stake, a frame L, secured to the side of the car, a pivotal pin which passes through the frame, and a car-stake, slotted at its lower end, and having both a vertical and a pivoted movement upon the pin, combined with the keepers F secured to the upper end of the stakes, the binding-rods D, the lock-lever E, and the rings K, substantially as shown.

JOHN S. MILLER.
